[57] CLAIM

The ornamental design for a grass cutting attachment
for use with chain saws and the like, as shown and
described.

DESCRIPTION

FIG. 1 is a top front perspective view of a grass cutting
attachment for use with chain saws and the like showing
my new design;

FIG. 2 is a right elevation thereof;

FIG. 3 is a top plan view thereof;

FIG. 4 is a front elevation thereof;

FIG. 5 is a bottom plan view thereof; and

FIG. 6 is a rear elevation thereof.
